UNITED STATES PATENT OFFICE.

AUGUST CHARLES, OF CHICAGO, ILLINOIS.

HARNESS.

SPECIFICATION forming part of Letters Patent No. 372,517, dated November 1, 1887.

Application filed August 19, 1887. Serial No. 247,330. (No model.)

To all whom it may concern:

Be it known that I, AUGUST CHARLES, a citizen of the United States, residing at Chicago, in the county of Cook and State of Illinois, have invented a new and useful Improvement in Harness, of which the following is a specification.

My invention relates, particularly, to an improvement in the collar portion of a harness, or to the part known as the "horse-collar," which encircles the horse's neck and commonly constitutes that feature of a harness involving it at which the pull of the load is exerted.

While my improvement relates to a collar, inasmuch as it is intended to encircle the neck of the animal and serve generally the purpose of a collar to the extent that it affords a suitable place of attachment for other parts of the harness, it does not constitute the feature at which the pull of the load is exerted in the same sense as in other collars, but affords pads having stiff outer surfaces and sufficiently broad to cover and conform to the shoulders of the animal, upon which the strain of the load is exerted, in a manner to maintain them in close contact with the parts they cover of the animal in all of its pulling movements, and thereby affords a flexible device which does not rub, and consequently chafe, the parts.

Ordinarily the collar portion of a harness is practically or in a high degree inflexible, fits around the neck, and extends down only upon the upper parts of the scapulae, where the latter are the weakest. The traces are connected directly with the collar, sometimes also with the hame, so that the strain of pulling is exerted mainly from the upper parts of the shoulder-blades and neck, thereby choking the animal, or at least straining it, owing to the resistance being brought to bear on the weaker portions of the scapulae. Besides, owing to the form and fit of the collar, and also to its degree of inflexibility, the shoulders in their alternate forward movements have to bear the entire or at least an unequal portion of the strain of the load consecutively, since the collar, as one shoulder advances, does not bear with equal pressure against the other shoulder, but is pulled and moved sidewise without remaining in contact with the other shoulder, thereby tending also to choke and chafe the animal.

It is my object to provide a collar the use of which shall not be attended with any of the foregoing disadvantages by constructing it to present a large surface, whereby it covers and conforms to both shoulders and is easy upon the horse while pulling; whereby the draft shall be exerted from the lower parts of the scapulae, where the main pressure is brought to bear and the greatest strength is exerted and without undue pressure upon the upper parts of the scapulae; whereby, owing to its flexibility and general construction, scalding and chafing shall be prevented and choking impossible, and whereby it shall be light and at the same time ornamental. It may also be stated that as an incident of my improved construction it avoids the necessity of employing an extra sweat-collar.

My invention consists in the general construction of my improvement; and it also consists in details of construction and combinations of parts, all as hereinafter more fully set forth.

In the drawings, Figure 1 is a partly-broken perspective view of a horse-collar of my improved construction, and Fig. 2 a section taken on the line 2 2 of Fig. 1 and viewed in the direction of the arrows.

A are plates of some stiff material—such as sheet metal, thin wood, or heavy sole-leather—and preferably bent to the shape illustrated, whereby they conform, at least approximately, to the parts they are intended to cover—namely, the shoulders of the animal for which the collar is designed.

It is not necessary, but only preferred, that the plates A shall conform in the manner described, since they may be straight and the padding underneath them, hereinafter described, shaped to conform to the shoulders.

B is the padding, comprising a suitable soft material or fabric stuffed with hair, wool, or the like, and covered by the plates A, which are secured to it. The padding is stuffed in a manner to cause it to conform on its inner surface to the shoulders of the horse, and is intended to extend down upon the animal sufficiently far to cover the shoulders. That part of the padding which extends above the plates A and serves to connect the plates and portions of the padding covered by them together, to produce the form of a collar, is simply pad-

ded material, forming integral extensions of the padded portions underneath the plates, although the last-named portions and the plates upon them may be two separate parts joined together by a strap to extend over the animal's neck and upon which to impose the hame C; or the hame may be padded above the plates and secured to the latter.

So far as the advantages of my improvement are concerned, it is immaterial to whichever of the foregoing constructions of collar it is applied, or whether a hame be provided or not.

The hame C, if provided, as shown, is applied to the collar in a usual manner.

D is a strap or band having at each extremity means for connecting the traces to it in the form of a hook, r, though I do not limit myself to any particular device for the attachment. The strap or band D is connected with the plates A, to extend transversely across them near their centers and in a manner to permit to it longitudinal play. The connection for the purpose may be through the means illustrated, comprising hooks q on the plates to hold flexible loops p, extending from the strap or band D, though any means which will connect or apply the part D to the plates in substantially the manner and for the purpose described will accomplish the desired result—as, for example, causing it to encircle the collar like a hame, and having the ends for the attachment of the traces crossed at the lower end of the collar to extend across the plates. If the ordinary breast-strap of the harness is used as the strap or band D, of course its connection with the harness maintains it in position against the plates A.

As the collar is divided, as shown, at its lower end, it may readily be placed in position upon the animal by spreading the lower disconnected ends asunder, when the hame serves to hold it against the sides of the neck, and the plates A and parts B of the collar underneath them extend sufficiently low to cover the shoulders; also, the collar being flexible, when the hame is once adjusted it need never be removed, since, owing to the manner it is secured upon the flexible collar—by the strap o—the collar may be expanded to slip over the horse's head, and the usual manner practiced of adjusting the common form of horse-collar—namely, by slipping it over the head in inverted position and then turning it while on the neck—need not be resorted to.

With the traces attached to the opposite ends of the strap D it will readily be seen that the load is pulled directly from the strap, and the strain forces the padded plates A equally throughout against the shoulders of the animal, to which they conform, as aforesaid. Owing to the longitudinal play afforded to the strap or band D by the manner of its connection to the collar, and to the flexibility of the latter above the plates, as the animal steps forward with one leg, the padded portion cover-

ing the shoulder of the other leg is held without rubbing against it by the strap D, and the last-named shoulder receives its due proportion of the strain. It is thus manifest that by means of my improvement the collar proper does not form the medium from which the strain of pulling is exerted, and therefore the objectionable consequences hereinbefore enumerated are avoided, and that, while it otherwise serves the general purposes of a collar, it constitutes a medium through which to transmit the strain of pulling to both shoulders simultaneously without chafing or choking the animal.

While the construction thus described is the preferred one through the medium of which to apply my improvement—viz., of producing the strain against pads covering the shoulders—the necessary stiffness or unyielding quality of the lower separated ends may be attained without employing extra plates A, by making the pads themselves at their lower ends sufficiently stiff and unyielding.

What I claim as new, and desire to secure by Letters Patent, is—

1. A horse-collar divided at its lower end, having the lower separated ends padded and stiffened and conforming to the shoulders of the animal, over which they extend to or substantially to the lower ends of the scapulae, and a flexible strap or band for connection at its opposite ends with the traces and loosely connected with the collar to extend across and bear flatwise against the upper surfaces of the said padded and stiffened ends, substantially as and for the purpose set forth.

2. A horse-collar divided at its lower end, having the lower separated ends padded to conform to the shoulders of the animal, over which they extend to or substantially to the lower ends of the scapulae, and surmounted by stiff plates, and a flexible strap or band for connection at its opposite ends with the traces and loosely connected with the collar to extend across and bear against the plates, substantially as described.

3. In a horse-collar, the combination of a padded portion, B, stiff plates A, and a flexible strap or band, D, loosely connected with the collar to extend transversely across the plates, substantially as and for the purpose set forth.

4. In a horse-collar, the combination of a padded portion, B, divided and conforming toward its lower end to the shoulders of the animal, over which it extends, stiff plates A upon the parts which cover the shoulders, and a flexible strap or band, D, connected to the collar by flexible loops p, to extend transversely across the said plates near their centers, substantially as and for the purpose set forth.

AUGUST CHARLES.
In presence of—

W.M. FREUND,
GEORGE C. COOK.
